(57) **CLAIM**

The ornamental design for a bridge saddle for electric guitar, as shown and described.

DESCRIPTION

FIG. 1 is a front perspective view of a bridge saddle for electric guitar, showing our new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is a cross-sectional view thereof taken along line 8-8 of FIG. 6; and,

FIG. 9 is a perspective view thereof as applied to an electric guitar bridge.

The broken lines are included for the purpose of illustrating environment only and form no part of the claimed design.
